MOBILE DISPLAY AND STORAGE CABINET

Bertram J. Cain, 1409 Oak Ave., Brookfield, Ill.

Filed Apr. 2, 1964, Ser. No. 79,321

Term of patent 14 years

(Cl. D80—11)

FIG. 1 is a perspective view of the mobile display and storage cabinet showing my design;

FIG. 2 is a front elevation of said cabinet;

FIG. 3 is a rear elevation of said cabinet;

FIG. 4 is a side elevation of said cabinet; and

FIG. 5 is a top plan view of the cabinet of FIG. 1.

The dominant features of my design reside in the portion shown in full lines.

I claim:

The ornamental design for a mobile display and storage cabinet, substantially as shown and described.
